UNITED STATES PATENT OFFICE

2,395,613

SALT AND PEPPER SHAKER

Oscar H. Crowell, Russellville, Ala.

Application September 30, 1943, Serial No. 504,453

1 Claim. (Cl. 65—45)

The present invention relates to new and useful improvements in salt and pepper shakers and has for its primary object to provide a container having separate compartments therein and a novel dispensing cap or top adapted to selectively discharge the contents of the respective compartments.

A further object is to provide means for easily and quickly removing the cap to permit filling of the compartments.

Another object is to provide a device of this character of simple and practical construction, which is neat and attractive in appearance, relatively inexpensive to manufacture and otherwise well adapted for the purposes for which the same is intended.

Other objects and advantages reside in the details of construction and operation as more fully hereinafter described and claimed, reference being had to the accompanying drawing forming part hereof, wherein like numerals refer to like parts throughout, and in which:

Figure 1 is a vertical sectional view.

Figure 2 is a vertical sectional view taken on a line 2—2 of Figure 1.

Figure 3 is a top plan view.

Referring now to the drawing in detail, the numeral 5 designates a container of plastic or other suitable material having an open top and provided with a partition 6 separating the container into a pair of compartments 7 and 8 adapted to contain different condiments, such as salt and pepper.

The upper edge of the partition is formed with a rib 9 which projects above the top of the container and is dovetail-shaped in cross section.

A cap 10 is constructed of parallel upstanding walls 11 having one edge resting on the walls of the container and also provided with a pair of inclined walls 12 and 13 converging at their lower edges at the center of the cap to form a web 14 having a channel 15 in its bottom edge adapted to conformably receive the rib 9. The cap is placed in position on the container and removed therefrom by sliding the cap across the top of the container with the rib fitted in the channel.

The inclined walls 12 and 13 merge at their upper edges with an adjacent side wall 11 of the cap and cooperate therewith to form chambers 16 and 17 in the cap in communication respectively with the compartments 7 and 8. The upper

portions of the walls 12 and 13 are perforated as shown at 18 and 19 to permit sifting of the contents therefrom when the container is inverted.

5 The perforations of the respective walls 12 and 13 may be closed by plates 20 and 21 hingedly connected on a pin 22 carried by the web 14 and a wire spring 23 is positioned between the plates 20 and 21 to urge the latter against the walls 12 and 13 to close the perforations therein.

A plunger 24 is attached to the plate 20 and projects laterally through the walls 12 and the adjacent wall 11 of the cap and is formed with a head or button 25 to manipulate the plunger, 15 while a similar plunger 26 is attached to the plate 21 and projects through an opposite wall of the cap.

Guides 27 are provided for loosely receiving the plungers in the chambers of the cap to prevent the contents from clinging thereto.

It is believed that the details of construction and manner of use of the device will be readily understood from the foregoing without further detailed explanation.

25 Having described the invention, what is claimed as new is:

A salt and pepper shaker comprising a container of polygonal shape in cross section and having a partition therein separating the same into a pair of chambers, said partition projecting outwardly at one end of the container to form a rib of dove-tail shape in cross-section, a dispensing cover having a partition therein separating the same into a pair of chambers to register with the chambers of the container, said last named partition having a channel in its lower edge adapted to conformably receive the rib, one end of the channel opening outwardly at one side of the cover to slidably receive the rib to secure the cover in position on the container, the opposed sides of the chambers in the cover being perforated, a pivoted closure for the perforated side of each of said last-named chambers, spring means positioned between said closures for urging the latter toward a closed position, and plungers slidably mounted in the cover and connected to the respective closures for opening the latter, said plungers extending in a direction at right angles to the rib to prevent sliding of the cover on the container by pressure exerted on the plungers.

OSCAR H. CROWELL.
